(57) **CLAIM**

The ornamental design for a current clamp, as shown and described.

DESCRIPTION

FIG. 1 is a front side elevational view of the current clamp;
FIG. 2 is a top plan view thereof;
FIG. 3 is a rear side elevational view thereof;
FIG. 4 is a bottom view thereof;
FIG. 5 is a left side elevational view thereof;
FIG. 6 is a right side elevational view thereof;
FIG. 7 is a front, right and top perspective view thereof;
FIG. 8 is a front, left and top perspective view thereof;
FIG. 9 is a rear, left and bottom perspective view thereof;
FIG. 10 is a rear side elevational view of the current clamp when opened;
FIG. 11 is a front side elevational view of the current clamp when opened;
FIG. 12 is a front, right and bottom perspective view of the current clamp when opened;
FIG. 13 is a front, right and top perspective view of the current clamp when opened; and,
FIG. 14 is a rear, left and top perspective view of the current clamp when opened.

The evenly broken lines depict environmental subject matter, specifically cables and their retaining slot, a housing above the lower handle, a cavity in the upper handle, a guide and stop structure, and plugs and sockets when the jaws are open, and form no part of the claimed design. The evenly dot-dashed lines near the guide and stop structure are boundaries limiting the extent of the claimed subject matter.
